(57) **CLAIM**

The ornamental design for a display screen with graphical user interface as shown and described.

DESCRIPTION

The patent or application file contains at least one drawing executed in color. Copies of this patent or patent application publication with color drawing(s) will be provided by the Office upon request and payment of the necessary fee.

Fig. 1: Front view

FIG. 1 is a front view of the image of a display screen with graphical user interface showing our new design; and the outer broken lines in the reproduction show a display screen and form no part of the claimed design.

1 Claim, 1 Drawing Sheet
